FIG. 5.

UNITED STATES PATENT OFFICE.

PETER LEPAK, OF PITTSBURGH, PENNSYLVANIA.

GUN-ADJUSTING MEANS.

1,285,253.

Specification of Letters Patent. Patented Nov. 19, 1918.

Application filed June 5, 1918. Serial No. 238,309.

To all whom it may concern:

Be it known that I, PETER LEPAK, a citizen of the United States of America, residing at Pittsburgh, in the county of Allegheny and State of Pennsylvania, have invented certain new and useful Improvements in Gun-Adjusting Means, of which the following is a specification.

The primary object of the invention is the provision of simultaneous adjusting means for a plurality of guns whereby the same may be lowered or elevated during the firing operation.

A further object of the device is the provision of a plurality of guns capable of adjustment for varying the angular distances between the muzzles of the guns comprising the device whereby the muzzles will hit a target in different relations upon firing the guns.

A still further object of the invention is to provide a triple gun mount adapted for radially shifting the guns simultaneously when sighting the same upon the enemy, the mechanism being easily operable at the breech end of the device.

In the drawings;

Figure 1 is a side elevation of the device;

Fig. 2 is a top plan view thereof;

Fig. 3 is a vertical longitudinal sectional view through the same;

Fig. 4 is a rear end elevation of the device;

Fig. 5 is a horizontal sectional view taken upon line V—V of Fig. 4; and

Fig. 6 is a vertical sectional view taken upon line VI—VI of Fig. 3.

Referring more in detail to the drawings, my device broadly consists of a mount 10 having an upright post 11 carried thereby to the head 12 of which three tapered guns 13 are hinged as at 14 for radial swinging movement, while an adjustable slider or spreader 15 changes the relative positions of the guns when being sighted for firing.

The head 12 upon the post 11 is circular in form with a rearwardly projecting hub 16 carried thereby through which the reduced portion 17 of a screw 18 is journaled. A wheel 19 is mounted upon the rear end of the screw 18 for convenience in turning the screw, being rearwardly of the breech block 20 of the guns 13, while the forward reduced end portion 21 of the screw is journaled in a post 22 forwardly of the post 11.

The spreader 15 is substantially tri-foil

or clover leaf in shape having circular openings 23 through each lobe 24 thereof for accommodating the guns 13 and by which arrangement the spreader 15 is slidably mounted upon the guns. The spreader 15 is provided with a hub 25 through which it is mounted in threaded engagement upon the screw 18 and whereby the slider 15 may be shifted to correct positions between the posts 11 and 22 by turning the hand wheel 19. Anti-friction rollers 26 may be provided in the lower sides of the slider openings 23 beneath the guns 13.

During the sighting of the guns, the hand wheel 19 may be turned for revolving the screw 18 in the required direction to rearwardly move the slider 15 toward the post 11 and which operation by reason of the tapering of the guns 13 simultaneously elevates the guns 13 and also draws the centers of the muzzles 27 upwardly and inwardly toward each other. Upon reversing the direction of the screw 18, the slider 15 is moved outwardly toward the post 22 permitting the guns 13 to lower and the muzzles of the two lower guns to slightly separate. The upper portion 28 of the forward hub 16 is detachable for convenience in assembling the device and from the foregoing description it will be seen that the aim of the shots from the guns 13 upon the target may be such as to elevate and concentrate or lower and scatter the same.

What is claimed as new is:—

1. A firing piece comprising a supporting post having a circular head, tapered guns hinged to the periphery of said head, a slider mounted upon said guns having openings through which the guns extend resting upon the slider, said post being positioned adjacent the rear ends of the guns, a forwardly positioned post upwardly extending between the lower guns, a screw threaded through said slider and journaled in said posts, and a turn wheel upon the rear end of the screw rearwardly of the guns.

2. A firing piece comprising a base, an upright post mounted thereon, a head upon said post having a rearwardly extending hub, three tapered guns hinged adjacent their rear ends to the periphery of the said head adapted for radial swinging movement, a forwardly positioned post, a screw journaled in said forwardly positioned post and hub, turning means for said screw rearwardly of the guns, and a slider supported

upon and threaded to said screw with said guns supported thereby.

3. A firing piece comprising a base, an upright post mounted thereon, a head upon said post having a rearwardly extending hub, three tapered guns hinged adjacent their rear ends to the periphery of the said head adapted for radial swinging movement, a forwardly positioned post, a screw jour-
naled in said forwardly positioned post and

hub, turning means for said screw rearwardly of the guns, a three lobed slider threaded upon said screw with an opening through each lobe of the slider having a gun supportingly extending therethrough, and 15 rollers carried by the slider at the bottoms of said openings beneath the guns.

In testimony whereof I affix my signature.

PETER LEPAK.
